UNITED STATES PATENT OFFICE.

JOHN A. WAGNITZ, OF COLUMBUS, OHIO.

FOLDING BOX.

1,080,610.

Specification of Letters Patent.

Patented Dec. 9, 1913.

Application filed May 13, 1912. Serial No. 696,870.

To all whom it may concern:

Be it known that I, JOHN A. WAGNITZ, a citizen of the United States, residing at Columbus, in the county of Franklin and State of Ohio, have invented certain useful Improvements in Folding Boxes, of which the following is a specification.

My invention relates to folding boxes and is particularly directed to the provision of 10 a foldable box structure of such a construction as to insure a maximum rigidity of formation when such formation is completed.

It therefore contemplates the provision of 15 hinged sides and ends which are readily foldable into operative position and which when in such operative position are rigidly maintained therein by the provision of a readily applicable spanning brace desirably disposed one at either end of the box structure.

Furthermore, in the embodiment of my 20 invention the spanning braces are desirably of such form and so disposed with relation to the complementary formation of the box structure that the assembled box structure 25 hides such spanning braces from view and consequently produces a neat and compact box.

The preferred embodiment of my invention is shown in the accompanying drawings, 30 in which similar characters of reference designate corresponding parts, and in which:

Figure 1 is a plan view of my box blank and the supplemental spanning braces there- 35 of, Fig. 2 is a detail of the end of my box blank showing one of the spanning braces applied and illustrating the preferred manner of application of such spanning element, Fig. 3 is a similar detail to Fig. 2 showing 40 the succeeding step in the formation of the box structure and showing the application of the staples which are desirably utilized, Fig. 4 is a representation of the next succeeding step and showing one end of the box 45 structure just short of completed position, Fig. 5 is a plan view of the box in its completed condition, Fig. 6 is a side elevation of the structure shown in Fig. 5, Fig. 7 is a section taken on line 7-7 of Fig. 5, and, Fig. 8 is a sectional detail taken on line 8-8 50 of Fig. 5.

In the drawings, the box is shown as com-

prising a base 1 desirably of rectangular formation, sides 2 and 3 and end pieces 4 and 5. These end pieces 4 and 5 are joined at their extremities to the side pieces 2 and 3 by corner pieces 6 and these corner pieces 6 are desirably scored or creased diagonally as at 7 having edges disposed to form a continuation of the normal edges of the box 60 ends and edges disposed to form continuations of the normal edges of the box sides. The edges of these corner pieces which form continuations of the end edges are desirably slotted as at 8 and these slots are designed 65 to coöperate with spanning braces in the form of strips 9 likewise slotted as at 10 near either end. Furthermore, the ends of the box are provided with supplemental integrally formed lips 11 which are designed 70 to fold over and embrace the strips 9 when in applied position.

By way of further description of the box structure, it may perhaps be more readily understood by the description of the manner 75 of formation and assembling. Thus, the strips 9 are applied, as shown in Fig. 2, having their slots 10 interfitting with the slots 8. In this position the sides 2 and 3 of the box are folded over into superimposed relation to the base 1. The end lips 11 are then folded over into embracing relation to the strips 9 where they are stapled centrally as shown in Fig. 3. In the next operation, the end pieces are folded upwardly with relation 80 to the base 1 and in their upward movement, the corner pieces are creased at the diagonal score or creasing 7. This manner of folding is illustrated by reference to Fig. 4 and it will be seen that in the upward 85 movement of the ends 4 and 5, the outer extremities of the lip 11 are forced upwardly by the formation of the corner pieces. Finally, these end lips 11 escape these corner pieces and assume the position shown in Fig. 95 7 when the box may be considered to be in completed condition.

It will be apparent that I have provided a simply formed box structure which is inherently rigid in its nature and which due 100 to its great simplicity of formation, is necessarily comparatively cheap.

What I claim, is—

A foldable box comprising a base, side

walls, end walls, corner pieces connecting said end and side walls and having slots therein, rectangular locking strips for each end of the box formed independently of said 5 end walls and being slotted in a manner to coöperate with the slots formed in said corner pieces to prevent spreading of the side walls, and staples for securing said locking

strips intermediate their ends to said end walls. 10

In testimony whereof I affix my signature in presence of two witnesses.

JOHN A. WAGNITZ.
